US00D837070S

(12) **United States Design Patent** (10) **Patent No.:** **US D837,070 S**
(45) **Date of Patent:** **** Jan. 1, 2019**

(54) **PILL ORGANIZER PACKAGE**

(71) Applicant: **NIPPON FRONTIER MEDICINE LABORATORIES, INC.**, Osaka (JP)

(72) Inventors: **Junichi Fukui**, Osaka (JP); **Kunihiro Musashi**, Osaka (JP); **Yoshinori Tanaka**, Osaka (JP)

(73) Assignee: **NIPPON FRONTIER MEDICINE LABORATORIES, INC.**, Osaka (JP)

(**) Term: **15 Years**

(21) Appl. No.: **35/502,766**

(22) Filed: **Nov. 1, 2016**

(80) **Hague Agreement Data**

Int. Filing Date: **Nov. 1, 2016**

Int. Reg. No.: **DM/095394**

Int. Reg. Date: **Nov. 1, 2016**

Int. Reg. Pub. Date: **Apr. 7, 2017**

(30) **Foreign Application Priority Data**

CLAIM

The ornamental design for a pill organizer package, as shown and described.

DESCRIPTION

1.-3. Pill Organizer Package

1.1 : Perspective

1.2 : Front

1.3 : Back

1.4 : Top

1.5 : Bottom

1.6 : Right

1.7 : Left

1.8 : Cross-sectional end view

1.9 : Perspective view with open lid

1.10 : Top view with open lid

1.11 is sectional view shown in environment,

2.1 : Perspective

2.2 : Front

2.3 : Back

2.4 : Top

2.5 : Bottom

2.6 : Right

2.7 : Left

2.8 : Cross-sectional end view

2.9 : Perspective view with open lid

2.10 : Top view with open lid

2.11 is a sectional view shown in environment.

No protection is sought for the matter shown in dotted lines (disclaimer); 1.8 and 2.8: cross-sectional end views cut perpendicularly at the left side of the center of the front view.

1 Claim, 22 Drawing Sheets
